Des. 204,330
Patented Apr. 5, 1966

204,330

CARD SORTER OR THE LIKE

Waldemar Wolf, Nurnberg-Reichelsdorf, and Otto Katz,
Schwabach, near Nurnberg, Germany, assignors to
Michael Maul, Schwabach, near Nurnberg, Germany

Filed July 20, 1964, Ser. No. 80,925

Term of patent 14 years

Claims priority, application Germany Feb. 29, 1964

(Cl. D64—11)

FIG. 1.

FIG. 2.

FIG. 3.

FIG. 4.

FIG. 1 is a front perspective view looking at the left thereof of a card sorter or the like showing our new design;

FIG. 2 is a front perspective view looking at the right thereof of the card sorter or the like;

FIG. 3 is a rear perspective view looking at the right thereof of the card sorter or the like; and

FIG. 4 is a top view of a card sorter or the like embodying our novel design.

The dominant features of our design reside in the portions shown in full lines.

We claim:

The ornamental design for a card sorter or the like as shown and described.
